INTERNAL CIRCULATORY HEATER

Paul R. McNamar, Garden City, Iowa

Application February 9, 1939, Serial No. 255,501

5 Claims. (Cl. 126—116)

This invention relates to an improved hot air stove or furnace.

It is an object of this invention to provide an improved hot air heater having an inner casing for heating air and an outer jacket spaced from said inner casing and provided with means for conveying the products of combustion by an inclined ascending route around said inner casing for heating the air contained therein.

10 Another object of the invention, is to provide automatic means for controlling the supply of fuel to said heater for maintaining a predetermined temperature therein; and means for automatically and adjustably controlling the release 15 of the combustion gases for obtaining the maximum of heat radiation therefrom.

Still a further object of the invention, is to provide a plurality of burners so disposed relatively to the inner air chamber and to its inlets 20 that the air passing into said chamber and in the bottom thereof will be directly heated by said burners in cooperation with the inclined ascending passages for heating the air as it passes upwardly through said heating chamber.

25 Other objects and advantages of the invention will hereinafter become more fully apparent from the following description of the drawings, which illustrate a preferred form thereof, and wherein:

30 Figure 1 is a side elevational view partly in section of a furnace or stove constructed in accordance with the invention.

Figure 2 is a vertical sectional view taken on the line 2—2 of Figure 1.

35 Figures 3, 4 and 5 are horizontal sectional views taken on the lines 3—3, 4—4 and 5—5, respectively of Figure 2, and

Figure 6 is a vertical central sectional view taken on the line 6—6 of Figure 4.

40 Referring more particularly to the drawings, wherein like reference characters designate like or corresponding parts throughout the different views, 10 designates generally the heater which may be either a stove or furnace and which includes the outer casing or jacket designated generally 11 having the legs 12 at its lower end forming the spaces 13 through which air is adapted to circulate. The outer casing 11 is provided with a horizontal partition 14 adjacent its top and with a rounded top forming with said partition the dome 15.

45 Mounted within the casing 11 and in spaced relationship to its side walls and to its partition 14 is an inner casing 16 provided with the four 50 depending pipes or conduits 17 which open out-

wardly at their lower ends and which are disposed in spaced apart relationship relatively to each other. As best seen in Figure 4, the side walls of the two casings 11 and 16 are disposed so that the adjacent walls of each casing are substantially parallel to each other inasmuch as the two casings are of substantially the same cross sectional shape. As illustrated, the heater 10 is rectangular in shape, but it is to be understood that it could likewise be of circular form if 10 desired. Casing 16 at its top is provided with the upwardly extending passages 18 which extend through the partition 14 to communicate with the dome 15 adjacent its opposite ends.

Between the inner and outer casings 16 and 11, respectively, are provided the continuous ascending vanes 19 which extend the length of the inner casing 16 to form the rectangular ascending passages 20 which extend from the space 21 below the casing 16 to the space 22 between the casing 16 and the partition 14.

Extending from the front through the rear of the dome 15 are the spaced parallel partitions 23 forming therebetween the draft passage 24 which communicates with the space 22 by means of the opening 25 formed in the partition 14. The rear portion of the draft passage 24 which extends beyond the rear wall of the casing 11 is provided with an annular flanged opening 26 at its top adapted to connect with a smoke flue, 30 not shown, and a smaller opening 27 in its bottom forming an air vent. Disposed above the opening 25 is a baffle 28 having an upwardly and forwardly extending oblique portion terminating in a horizontal portion at its free end to 35 direct fumes and the products of combustion which enter the draft passage 24 toward the front thereof. Behind the baffle 28 is a damper 29 which is pivotally mounted intermediate of its ends and which is provided with an arm 30 disposed obliquely to the plane thereof. A flap valve 31 is pivotally connected at 32 to control the opening 27 and is likewise provided with an arm 33 disposed obliquely thereto and connected to the free end of the arm 30 by means of the 40 rod 34 which extends through a slot 34' in the damper 29. An angular shaped arm 35 is secured to and depends from the underside of the valve 31 with its free end disposed substantially parallel to the plane of said valve. Mounted on 45 said parallel portion is a counterbalance 36 provided with a set screw for adjustably positioning it. The parallel portion of the arm 35 extends inwardly toward the casing 11 so that by moving the counterbalance 36 outwardly 50

55

relatively thereto the downward pressure on valve 31 will be increased to urge it toward a closed position. As seen in Figure 1, damper 29 and valve 31 are so connected by means of the rod 34 that as the valve 31 closes the damper 29 will be opened and conversely, in order to control the draft through the draft jack 24.

A plurality of burners 37 are disposed beneath the casing 16, in the space 21, between and in spaced relationship to the inlet pipes 17, each of said burners being provided with a manually controlled valve 38 adapted to be disposed adjacent the openings 39 in the lower part of the outer casing 11 for selectively controlling and adjusting the burners 37. Burners 37 are all connected to a common supply pipe 40 which connects with a storage tank 31 mounted behind the heater 10. Disposed in the pipe line 40 is the T-joint, designated generally 41 the two arms 20 42 and 43 of which form a part of the pipe line 40, said arms being connected to the pipes 44 by means of conventional socket nuts 45 to form a liquid tight connection. Connected to the third, upwardly extending branch 46 of the joint 41, by 25 means of the nut 47 is the free end of the pipe 48 which forms a part of the casing 49 which is provided with the openings 50. A thermostat 51, of any conventional construction, is mounted in the casing 49 and adjustably supported therein by means of the set screw 52 which extends through the top thereof. Thermostat 51 is provided with a depending needle valve 53 which is loosely disposed in the bore of the pipe 48 and of the branch 46, and which 30 is provided with a tapered end 53' adapted to seat in the tapered portion 54 of the bore of the branch 42 to close or partially close the pipe line 40.

From the foregoing it will be seen, that the 40 burners 37 will receive fuel through the pipe line 40 to heat the pipes 17 and the bottom of the casing 16. The air will be drawn inwardly through the openings 13 and upwardly through the pipes 17 into the casing 16 being heated during this passage. The products of combustion, from the burners 37 will pass upwardly through the passages 20 by a circuitous route around the casing 16 to heat the sides thereof to increase the heat of the air therein, said products of combustion passing through opening 25 into the draft passage 24 and out through the opening 26 to the smoke flue. The heated air in the chamber 16 will pass upwardly therefrom through the passages 18 into the headers 55 in the dome 15, 50 which are heated by the products of combustion passing through the space 22. Headers 55 are provided with one or more outlets 56, which may open outwardly into a room or which may connect with pipes leading to a plurality of rooms to release or carry off the heated air. The thermostat 51 is disposed adjacent to the outer casing 11 and is responsive to the heat thereof to be expanded as the heat increases to move the needle valve 53 downwardly to decrease the opening between its end 53' and the tapered valve seat 54 to decrease the amount of fuel permitted to pass through the supply pipe 40. The valve portion 53' and the valve seat 54 are so arranged, that when the valve is in a fully closed position a slight amount of fuel may still pass therethrough, said amount being sufficient to merely keep the burners 37 lighted.

Various modifications and changes in the construction and arrangement of the parts forming the invention may obviously be made and are

contemplated, as the drawings and description are only intended to illustrate a preferred embodiment thereof, and the right is therefore reserved to make such variations and changes as fall within the spirit and scope of the invention 5 as hereinafter defined by the appended claims.

I claim as my invention:

1. A device of the class described comprising an outer casing, an inner casing disposed in spaced relationship to said outer casing and 10 provided with depending conduits, continuous ascending vanes disposed between said casings and forming ascending passages, said outer casing being provided with a horizontal partition above said inner casing having a substantially 15 centrally disposed opening, the top of said outer casing forming a head having a central compartment communicating with said opening and with a smoke flue, passages connecting said inner casing, at its top, with the remaining portion of 20 said head, said remaining portion being provided with outlet openings, and burners mounted in said outer casing beneath said inner casing and above the lower ends of said depending conduits to heat the conduits and the bottom of said inner 25 casing directly, the products of combustion passing upwardly from said burners through said ascending passages to heat the sides and top of said inner casing, and the air in said inner casing passing upwardly through the passages at its 30 top into said head to be exhausted outwardly therefrom.

2. In a device of the class described, a heater comprising inner and outer casings disposed in spaced relationship relatively to each other, as 35 ascending vanes disposed between said casings forming a plurality of ascending passages, burners disposed beneath said inner casing and within said outer casing, conduits depending from said inner casing and opening beneath said burners to convey air upwardly through the inner casing to be heated by said burners, said outer casing being provided with a dome disposed above and in spaced relationship to said inner casing and having a centrally disposed draft passage 45 communicating with said ascending passages and with a smoke flue, and a plurality of passages connecting said dome and inner casing.

3. A device as in claim 2, said draft passage being provided with a damper, an air valve 50 mounted in said draft passage and provided with an adjustable counterbalance, and means connecting said damper and valve for adjustably and automatically controlling the draft to said smoke flue.

4. A hot air furnace comprising an outer casing having openings adjacent its bottom to admit air, an inner casing mounted in the outer casing, ascending vanes mounted between said casings and forming a plurality of circuitous ascending 60 passages, tubes depending from the inner casing and opening adjacent the bottom of the outer casing, a plurality of burners disposed beneath the inner casing and above the lower ends of said tubes, said outer casing having a horizontal 65 partition disposed above and spaced from the inner casing and forming a dome, partitions dividing said dome into a plurality of compartments including a center smoke passage having an opening in its bottom connecting with the 70 space above the inner casing for receiving the products of combustion therefrom, a baffle for directing the products toward one end of said passage, an outlet in the opposite end thereof, an adjustable automatically controlled damper 75

mounted in the passage between the baffle and outlet, said other compartments being heated by said passage, said last mentioned compartments being provided with outlets and with passages connecting with the inner casing.

5. A hot air furnace comprising an outer casing having a dome at its top, an inner casing spaced from the outer casing and dome, a burner disposed beneath the inner casing, tubes depending from the inner casing and opening beneath the burner, ascending vanes connecting the side

walls of the casings and forming ascending passageways, said dome having an opening communicating with the space above the inner casing, a smoke passage in said dome communicating with said opening, a smoke stack rising from said smoke passage, a damper disposed between said opening and smoke stack, and tubular conduits connecting the top of the inner casing and said dome, said dome having outlets for the heated air from the inner casing. 5
